WASHING MACHINE

Leo M. Harvey, Los Angeles, Calif.

Application August 14, 1940, Serial No. 352,582

3 Claims. (Cl. 68—140)

This invention relates to washing machines and relates more particularly to clothes washing machines for use in commercial laundries, etc. A general object of this invention is to provide a practical, effective, clothes washing machine for carrying on cyclic or stage washing operations that is of improved and simplified construction.

Another object of this invention is to provide a washing machine of the character referred to as having a strong, rigid, frame of novel design, embodying a minimum of parts and materials.

Another object of this invention is to provide a washing machine of the character referred to in which the stationary washing shell is mounted and arranged to brace the end members of the frame and thus lend rigidity to the entire frame structure.

Another object of this invention is to provide a washing machine of the character referred to in which the shell is formed to permit removal of the entire rotatable or oscillatable cylinder without disturbing the frame and without removing the shell.

Another object of the invention is to provide a commercial washing machine embodying a rotatable or oscillatable cylinder of improved design and construction.

Another object of this invention is to provide a washing machine of the character referred to in which the trunnion mountings for the cylinder are removable for repair and replacement and in which the bearings and seals for said mountings are easily accessible for reconditioning, repair, etc.

Another object of the invention is to provide novel means for holding the cylinder door firmly closed to strengthen the cylinder structure and to prevent buckling of the door.

Another object of this invention is to provide a washing machine of the character referred to including a pre-mixing tank for receiving the sours, soaps, bleaches, bluing, etc. and hot and cold water for the cyclic washing operations, arranged to discharge the resultant solutions into the washing shell and equipped with hot and cold water lines which discharge across a sloping bottom wall of the tank to effectively flush clear the soaps, etc. and to put the washing materials into solution so that well mixed and homogeneous washing mixtures are supplied to the washing shell.

A further object of this invention is to provide a washing machine of the character referred to embodying a novel fluid pressure op-

erated and remotely controlled dump valve for the washing shell which is positive in operation and self-equalizing or self-balancing to always make a tight seal when closed.

The various objects and features of my invention will be fully appreciated from the following detailed description of a typical preferred form and application of my invention, throughout which description reference is made to the accompanying drawings, in which:

Fig. 1 is a front, perspective view of the washing machine provided by this invention. Fig. 2 is an enlarged vertical detailed sectional view of the machine taken in a plane which intersects the longitudinal axis of the shell and cylinder. Fig. 3 is an enlarged fragmentary vertical detailed sectional view taken on the central longitudinal axis of the machine and illustrating an end portion of the machine. Fig. 4 is an enlarged fragmentary vertical detailed sectional view taken as indicated by line 4—4 on Fig. 3. Fig. 5 is an enlarged fragmentary vertical detailed sectional view of the cylinder and a portion of the cylinder door. Fig. 6 is a fragmentary vertical detailed sectional view illustrating the valve of the pre-mixing tank. Fig. 7 is an enlarged fragmentary sectional view illustrating the means for securing the removable shell section, and Fig. 8 is an enlarged fragmentary sectional view of the means for guiding the cylinder door.

The washing machine of the present invention may be said to comprise, generally, a frame 10, a washing shell 11 mounted in the frame 10, a rotatable or oscillatable cylinder 12 supported in the frame 10 to turn in the shell 11, means 13 for operating the cylinder 12, means 14 for supplying the washing materials, water and solutions to the shell 11, and a dump valve 15 for the shell 11.

The dump valve 15 is the subject matter of my co-pending application entitled Drain valves for washing machines and the like, Serial No. 411,051, filed September 16, 1941.

The frame 10 serves to support the various elements of the machine and is characterized by its simplicity and low cost. The frame 10 includes two spaced upright end members 16. The end members 16 are plate-like parts and are generally rectangular in face view. Strengthening channel irons or corner members 17 are secured to the vertical edges of the end members 16 at their outer sides. The ends of the corner members 17 and the lower parts of the end members 16 rest on feet 18 which in turn rest on bed members or runners 19 of I-beam stock, or the like. The end

members 16, corner members 17, feet 18 and runners 19 are rigidly secured together as by welding. The runners 19 are adapted to rest on the floor and may be suitably fixed in place. A pair of spaced angle members 20 extend between and connect the runners 19. The transverse connecting members 20 may be welded to the runners 19. A pair of horizontal connecting members 21 are engaged on the upper edges of the end members 16 adjacent the rear of the frame 10. The connecting members 21 are preferably fixed to the end members 16 by welding. A front frame member 22 of channel stock extends between and connects the upper forward parts of the end members 16. The ends of the front frame member 22 may be welded to the inner sides of the end members 16. A pair of spaced horizontal supporting and bracing members 23 extend between and connect the end members 16. The members 23 are spaced below the upper horizontal members 21 and are positioned to have parts or flanges lying in a common horizontal plane. As illustrated the members 23 may be formed of angle iron. The opposite ends of the supporting and bracing members 23 may rest on and may be secured to cleats 24 fixed to the inner sides of the end members 16. While I have described the several parts of the frame 10 as welded together it is to be understood that the frame parts may be bolted, riveted, or otherwise secured together. It will be observed that the frame 10 is a simple strong structure and is such that it may be quickly assembled.

The shell 11 houses the rotatable or oscillatable cylinder 12 and serves as a container for the water, washing solutions, etc. In accordance with the invention the shell 11 is a cylindrical, horizontally disposed structure positioned between the end members 16 of the frame 10. The shell 11 includes a pair of disc-shaped ends 25 positioned adjacent the end members 16 of the frame. The shell ends 25 are spun or otherwise formed to have central raised or outwardly projecting parts 26 adapted to bear against the inner surfaces of the end members 16, see Fig. 3. Ring-like fittings 27 are positioned in the central parts 26 and have annular flanges 28 which project outwardly through central openings in the parts 26 and end members 16. Studs 29 are threaded in openings in the fittings 27 and extend outwardly through openings in the parts 26 and end members 16. Nuts 30 are threaded on the studs 29 and clamp against the end members 16 to secure the parts 26 and the fittings 27 to the end members. Grooves 31 are formed in the fittings 27 and when the structure is assembled a suitable sealing material is arranged between the fittings and the parts 26 to be retained in the grooves 31 and to form effective seals between the shell ends and the frame end members 16. Out-turned rims or flanges 32 are provided on the peripheries of the disc-like ends 25.

The shell 11 further includes a cylindrical structure extending between and carried by the ends 25. This structure comprises two sections, namely, a permanent or fixed section 33 and a removable section 34, see Fig. 2. The sections 33 and 34, when connected, form a complete circle or cylinder. The fixed section 33 is of greater circumferential extent than the section 34 extending for about 210° and is positioned to form the rear or inner section of the shell 11. The end portions of the section 33 telescope over the flanges 32 and are secured and sealed with the flanges. Seam welds 35 may serve to connect the

ends of the section 34 and the flanges 32 and form complete, continuous seals between the sections and the end flanges. If desired, the section 33 may be spot-welded to the flanges 32 to locate the parts for the seal welding operation and to assist in connecting the parts. Curved angle iron members 36 are bolted to the inner sides of the frame end members 16 and welds 37 may connect the section 33 and the angle iron members 36, see Fig. 3. It will be seen that the members 36 assist in securing the cylindrical shell 11 to the end members 16 of the frame 10 and give rigidity to the structure. The shell 11 fixed to the end members 16 by the studs 29 and nuts 30 and by the angle members 36 forms an effective brace and tie rigidly connecting the end members of the frame 10. While it is contemplated that the main section 33 of the shell 11 may be formed of a single sheet of stock it may be preferred to form the section of two or more parts in which case the parts are connected by lap seams 38 sealed with solder or the like and welded or riveted.

The removable section 34 is the front section of the shell 11, serving to close the front of the fixed section 33. The longitudinal edge portions of the sections 33 and 34 have telescopic cooperation. Angle irons 39 extend along the sections 33 and 34 adjacent their longitudinal edges and bolts 40 removably or detachably connect the angle irons 39. The angle irons 39 are preferably spaced one from the other so that the sections 33 and 34 are tightly drawn together and the engaging telescoping parts of the sections are related to closely fit one in the other to provide fluid tight seals. The end parts of the removable shell sections 34 overlap the flanges 32. Bands 41 are arranged against the inner sides of the flanges 32 and somewhat wider bands 42 are arranged against the exterior of the section 34 along its edges. Screws 43 are passed through openings in the bands 42, the section 34 and the flanges 32 and are threaded into openings in the bands 41 to detachably secure the edge portions of the section 34 to the ends 25. It will be seen that the section 34 is easily detached upon removing the bolts 40 and the screws 43.

An opening 44 is provided in the section 34 to allow the clothes to be placed in the cylinder 12 and to permit the easy removal of the clothes. The opening 44 is spaced between the ends of the shell 11 and extends downwardly from the upper edge of the removable section 34. A door 45 is provided to normally close the opening 44. The door 45 is curved to conform to and complete the section 34. The door 45 may have circumferentially extending raised ridges 46 to increase its rigidity. Means is provided for guiding the door 45 for movement between its open and closed positions. This guide means is best illustrated in Fig. 10 of the drawings. The door guiding means includes guides 47 grooved at their inner edges as shown by 48. The guides 47 extend along both longitudinal edges of the opening 44 and the lower edge of the opening. Rivets or the like may fix the guides 47 to the shell section 34. The grooves 48 of the guides 47 slidably receive the edge portions of the door 45. Bands 49 are removably secured to the guides 47 by screws 50 and extend over the grooves 48 to slidably guide and retain the longitudinal edge portions of the door 45. A handle 51 may be secured to the door 45 adjacent its longitudinal edge. The door 45 normally remains in its closed position by gravity where its lower edge portion is received in the groove 48 of

the guide 47 which extends along the lower edge of the opening 48. Upon removal of the bands 49 the door 45 is free for detachment from the shell.

The cylinder 12 is a foraminous or perforated hollow member arranged in the shell 11 for rotation or oscillation by the means 13. The cylinder 12 is positioned in concentric relation to the shell 11 and is received in the shell with substantial clearance. The clothes receiving cylinder 12 includes ends 52 of sheet metal or the like and cast wheels 53 on the outer sides of the ends 52. Flanges 54 on the margins of the ends 52 are recessed in the peripheries of the wheels 53. The wheels 53 have outwardly projecting annular rims 55 and central thickened hubs 56. The invention provides novel and very effective means for removably and rotatably supporting the cylinder 12. This means includes trunnions 57 removably attached to the wheels 53. The trunnions 57 are provided at their inner ends with broadened bases 58 which are removably secured to the wheel hubs 56 by screws 59. The screws 59 may be keyed or locked by a wire 60. The trunnions 57 extend outwardly from their bases 58 and project through carriers 61 received by the above described fittings 28. The outer portions of the studs 29 extend through openings in the carriers 61 and nuts 62 are threaded on the studs to removably secure the carriers 61 to the ends of the frame 10. Outwardly opening sockets 63 are provided in the carriers 61 and grooves in the carriers at the inner ends of the sockets serve to contain packing or sealing assemblies 64. The sealing assemblies 64 prevent the leakage of fluid around the trunnions 57.

Anti-friction bearings are provided in the carriers 61 to rotatably support the trunnions 57. The bearings include cartridges 65 inserted in the sockets 63 and removably secured to the carriers 61 by bolts 66. Anti-friction bearing elements 67 cooperate with races in the cartridges 65 and bushings 68 on the trunnions 57 to support the trunnions for free rotation. Rings 69 are threaded in the outer ends of the cartridges 65 to retain the anti-friction bearing elements 67 and the outer races. Thrust rings 70 are secured to the outer parts of the bushings 68 by screws, or the like. It will be observed that the screws 66 may be removed to permit removal of the bearings so that the packing assemblies 64 are exposed for replacement or repacking. When the carriers 61 are detached from the frame ends 10 the screws 66 are exposed for removal and the trunnions 57 may be withdrawn through the fittings 21. The means for rotatably supporting the cylinder 12 is such that it may be reconditioned and replaced from time to time and is such that the cylinder may be freed for removal from the shell 11. Drain ports 73 are provided in the lower portions of the carriers 61 and lead outwardly from the inner parts of the sockets 63. Leakage through the ports 73 indicates that the packing or sealing units 64 require attention.

The cylinder 12 further includes a tubular cylindrical assembly secured between the ends 52. This tubular assembly is made up of a number of arcuate sections 72. The sections 72 are provided with multiplicities of perforations 74 so that the water, washing mixtures, etc. delivered to the shell 11 reach the clothes in the cylinder 12. The perforations 74 are spaced apart throughout the extents of the sections 72 and are of such size and form that buttons and other parts on the clothes cannot catch in them. Out-

wardly turned flanges 75 extend along the longitudinal edges of the cylinder sections 72.

The invention provides novel lifting ribs 76 for lifting and agitating the clothes as the cylinder 12 rotates or oscillates. The lifting ribs 76 are elongate channel-shaped or U-shaped members having curved inner parts and flat, generally parallel side parts. The ribs 76 extend throughout the length of the cylinder 12 and have their ends at the cylinder ends 52. The lifting ribs 76 are embodied in the cylinder 12 in a novel manner. The ribs 76 project radially inward from the internal surface of the cylinder 12 and occur where the longitudinal edges of the sections 72 are joined. Each rib 76 has an inturned lip or flange 77 extending along one longitudinal edge. The inturned flanges 77 are welded or otherwise fixed to the sections 72. There is a rib 76 secured to one longitudinal edge portion of each cylinder section 72 and the flanges 77 of the ribs are secured to the sections prior to assembling the cylinder. Each rib 76 has a longitudinal edge portion 78 extended outwardly to be received between the opposing flanges 75 of a pair of adjacent sections 72. Rivets, bolts 79 or other securing members are passed through openings in the opposing flanges 75 and the edge portions 78 of the ribs 76 to connect the sections 72 and to secure the edge portions of the ribs 76. It will be seen how each rib 76 is secured to a section 72 by the welds at the flanges 77 prior to the assembling of the sections 72 and how the connection of the several sections 72 by the bolts 79 completes the securing of the ribs 76 to the cylinder sections. It will be observed that the ribs 76 are secured to the internal surface of the cylinder 12 without leaving exposed bolt head, rivet heads, or the like, that might catch or injure the clothes. The opposite ends of the ribs 76 are provided with out-turned flanges 78 that are bolted, riveted, welded, or otherwise secured to the ends 52 of the cylinder. The cylinder structure is reinforced by longitudinal tie rods 80. The tie rods 80 extend through the hollow lifting ribs 76 and pass through openings in the ends 52 and the wheels 53. Nuts 81 are threaded on the projecting end portions of the tie rods 80 to engage against the wheels 53. The rods 80 materially strengthen the cylinder 12. It will be observed that the ribs 76 form shields and housings for the tie rods 80.

The cylinder 12 is provided with an opening 82 through which the clothes are passed. A door 83 normally closes the opening 82. The door 83 is shaped to conform to and complete the cylinder 12 and is perforated in the same manner as the cylinder sections 72. The opening 82 preferably extends upwardly from the lower edge of one of the sections and is preferably spaced between the ends of the section. Guide means 84 similar to or identical with the above described guide means 47-48-49-50 is provided at the opening 82 to guide the door 83 for movement between its open and closed positions. Stop strips 85 extend along the upper edges of the door 83 and opening 82 and have pitched faces 86 that cooperate when the door is in the closed position to bind or wedge the door so that it does not work or rattle.

Improved latch means is provided to hold the door 83 in its closed position. The latch means includes a pair of catches or hooks 87 secured to the cylinder 12 adjacent the lower edge of the opening 82. The hooks 87 are arranged to face or oppose one another. Flanges on the

hooks 87 are secured to the adjacent flanges 75 of the cylinder 12 by bolts 88. In accordance with the invention shims 89 are arranged between the bases of the hooks 87 and the cylinder flanges 78. By removing the shims 89 the hooks 87 may be adjusted to compensate for wear in the latch means. The latch means further includes a hollow or concave carrier 91 set in a horizontal opening 92 in the lower portion of the door 83 and secured to the door by rivets, welding, or the like. Latches 93 are supported in cooperating relation to the hooks 87 by pivot pins 94 on the carrier 91. The latches 93 are lever-like elements and have main outer arms of hooklike formation provided with curved noses 95 for cooperating with the hooks 87. The latches 93 further include inner arms that are forked to each have two spaced lugs 96 and 87, see Fig. 4.

Spring-loaded toggle structures are provided for the control and operation of the latches 92. Tongues 98 are received by the latch lugs 96 and 87 and are pivotally connected therewith by pivot pins 99. The pins 99 are spaced some distance from the pivotal axes of the latches 93. Mounting lugs 100 are provided in the carrier 91 and yoked members 101 are secured to the lugs 100 by pivot pins 102. The tongues 98 and the members 101 have slidably cooperating telescoping stems 103 and compression springs 104 surround the telescoping stems 103 and are engaged under compression between the shoulders on the tongues 98 and members 101. The tongues 98 and the members 101 constitute extensible and contractible spring-loaded toggle levers or links. The pivotal connections 99 of the tongues 98 with the latches 93 are located so that the springs 104 serve to urge the latches to the active or released positions, depending upon the positions of the pivot pins 99 relative to lines drawn between the pivot pins 94 and 102. In other words, the toggle structures are adapted to be operated to throw the pivot pins 99 over center between the position illustrated in Fig. 3 of the drawings and a position where the latches 93 are released from the hooks 87. The lugs 87 are adapted to engage against stops 105 on the carriers 91 to limit the opening movement of the latches 93.

The means for the control and operation of the latches 93 include handles 106 pivotally mounted in the carrier 91. In the structure illustrated the handles 106 are pivotally supported by the posts 107 formed in the carrier 91. Links 108 are pivotally connected with the rear or inner ends of the handles 106 by pivot pins 109 and extend outwardly to the adjacent latches 93. The links 107 may be flat rods and their outer parts may be twisted to lie parallel with the inner sides of the lugs 96. Slots 110 are formed in these twisted outer parts of the links 108 and pivot pins 111 on the lugs 96 cooperate with the slots 110 to connect the links with the latches 93. Extensible coiled springs 112 are secured to the links 108 and the interior of the carrier 91 to yieldingly hold the handles 106 against movement and to take up play at the slots 110 so that the handles do not work or swing when the machine is in operation. The springs 112 are much lighter than the springs 104 and do not interfere with the action of the spring-loaded latches 93. The handles 106 normally occupy positions in the carrier 91 where they extend substantially parallel with the longitudinal axis of the cylinder 12. The springs 112 serve to retain the handles in these positions.

By manually swinging the handles 106 out-

wardly the latches 93 are pivoted to throw the pivot pins 99 over center and to release the latch noses 95 from the hooks 87. The springs 104 retain the latches 93 in the released positions until the handles 106 are manually returned to their normal positions. When this is done the pivot pins 99 are thrown over center to their original positions and the springs 104 serve to hold the latches in their active positions. As best illustrated in Fig. 3 of the drawings the latch noses 95 have curved faces which cooperate with the hooks 87. These curved faces of the latch noses 95 are of considerable length and the latches and hooks are related so that the curved faces of the latch noses 95 continue to be maintained in proper latching engagement with the hooks 87 as the hooks and latches wear. The long noses 95 of the spring-held toggle latches continue to be operative even after extensive wear has occurred on their outer portions. By adjusting the shims 90 the hooks 87 may be set to have proper holding engagement with the latch noses 95 after extensive wear of both the hooks and latches has taken place.

The cooperation of the latches 93 with the hooks 87 at one end of the door and the engagement of the tapered stops 85 and 86 at the other end of the door holds the door 83 under tension so that the door strengthens the entire cylinder 12.

The door is tightly held closed by the means just mentioned so that the clothes striking the inner surface of the door cannot spring or loosen the door.

The means 13 for operating the cylinder 12 is a power driven means including an electric motor 114. The motor 114 is preferably, although not necessarily, a reversible electric motor having a reversing means 115. A speed reduction means 116 is preferably associated with the motor 114. The present invention is not primarily concerned with the details of the motor 114, the reversing means 115, or the speed reduction 116. The motor 114 and its associated parts are supported in the upper part of the frame 10. I have shown the motor 114 resting on a plate 117 which in turn is secured to the horizontal frame members 23. The plate 117 has slots 118 and bolts or studs 119 pass through the slots to secure the motor 114. The motor 114 is arranged so that its shaft or the shaft of the speed reduction 116 projects outwardly at one end of the frame 10 in parallel relation with the cylinder trunnions 57. A sprocket 120 is fixed to the shaft of the motor 114 or the shaft of the gear means 116. A larger sprocket 121 is keyed or fixed to the trunnion 57 at the same end of the washer frame 10 and a chain 122 operates over the sprockets 120 and 121 so that the motor 114 may drive or turn the cylinder 12. The motor 114 is governed or controlled by a control mechanism 123 suitably mounted on the frame 10. The mechanism 123 controls the several elements of the washing machine to provide for the cyclic or stage washing operations and forms the subject of a co-pending application. The drive between the motor 114 and the cylinder trunnion 57 is housed in a suitable case 124. The case 124 is secured to one end of the frame 10 to enclose the sprockets 120 and 121 and the chain 122. By loosening the bolts or nuts 114 may be shifted or adjusted as required.

The means 14 for supplying the water and washing materials to the shell 11 includes a mixing tank or premixing tank 125. The tank 125

is mounted in the frame 10 above the shell 11. The forward portion of the tank 125 may be supported on and secured to the frame member 22 while the rear portion of the tank may be supported by the horizontal supporting members 23. The sides of the tank 125 are vertical or upstanding and the tank has an open upper end. The top or upper end of the tank 125 is partially closed by a shield or apron 126 extending forwardly and then upwardly to project above the foremost upper frame member 21. The bottom of the tank 125 has a wall 127 that slopes downwardly and rearwardly from the front wall of the tank. The sloping wall 127 may extend between the opposite ends of the tank 125 and its slope or pitch is increased toward the back of the tank. A substantially horizontal wall 128 rests on and is secured to the frame members 23 and forms the rear portion of the tank's bottom. Hot and cold water pipes extend to the machine and are controlled by valves 129. The valves 129 are carried by a base 130 which in turn is fixed to the upper horizontal frame members 21. The discharge lines 131 leading from the valves 129 extend downwardly and forwardly in the tank 125 to have their discharge ends in the forward portion of the tank above the sloping wall 127. The hot and cold water pipes 131 preferably discharge from adjacent one end wall of the tank 125 toward the opposite end wall of the tank and their points of discharge are spaced apart horizontally. The pipes 131 are sloping so that the fluid cannot be trapped or retained in them. Nozzles or fluid spreaders 8 are provided on the pipes 131 to spread or spray the water across the bottom of the tank 125 to prevent the washing materials from accumulating thereon.

The means 14 further includes a plurality of containers 132 arranged to discharge into the pre-mixing tank 125. The containers 132 are pivotally supported on brackets 133 carried by the front frame member 22 and are arranged to dump or empty by gravity. Solenoid latches 134 are provided to initially or normally hold the containers 132 in their upright positions. The containers 132, the brackets 133 and the solenoid latches 134 are fully described and claimed in a co-pending application entitled "Material dispensing means" filed August 14, 1940, Serial No. 352,586. The containers 132 are positioned to discharge into the forward portion of the tank 125 so that their discharging contents are acted on or flushed by the water discharging from the pipes 131. The water discharging under pressure from the pipes 131 is adapted to completely flush away material discharged from a container 132 so that the material is thoroughly mixed with the water in the tank 125.

The means 14 further includes a valved outlet which discharges into the washing shell 11. This outlet includes a tubular valve seat fitting 135 arranged at an opening in the horizontal lower wall portion 128 of the tank 125 and an elbow fitting 136 secured to the rear portion of the shell 11 and discharging into the shell. A flexible sleeve 137 is clamped to the adjacent ends of the fittings 135 and 136 to form a flexible coupling between the fittings. A valve 138 is adapted to engage down against a seat surface on the fitting 135 to close the same. The valve 138 has a depending stem 139 guided by a web 140 in the fitting 135 and has an upstanding stem 141 extending upwardly in the tank 125. A solenoid coil 142 is mounted on the plate 130 and has a downwardly projecting operating rod 143. A stirrup

144 is secured to the lower end of the rod 143 and engages about the valve stem 141. The stirrup 144 is adapted to engage upwardly against a nut 145 on the stem 141 when the coil 142 is energized to open the valve 138. The valve operating coil 142 is controlled by the timing mechanism 123. In the cyclic operation of the machine the tank 125 receives a given quantity of water from a pipe 131 or from the two pipes 131, the quantity being determined by the operation of the valves 129 under the control of the mechanism 123, and may receive a sour, soap, bleach, bluing, or the like, from one or more of the containers 132 which material is mixed with the water in the tank. The water or the water mixture remains in the tank 125 until the coil 142 is operated to open the valve 138 whereupon the water or the water mixture discharges into the washing shell 11.

20 The washing machine of the invention includes a steam delivery means and an appropriate control for providing selected temperatures in the washing shell 11. The present invention is not primarily concerned with the steam delivery or control means, this means being the subject matter of a co-pending application entitled Temperature control means for washing machines and the like, filed August 14, 1940, Serial No. 352,583. Fig. 2 of the drawings shows a steam line 180 entering the frame 10 from its rear and a control 181 for the steam line 180.

Having described only a typical preferred form and application of my invention, I do not wish to be limited or restricted to the specific details herein set forth, but wish to reserve to myself any variations or modifications that may appear to those skilled in the art or fall within the scope of the following claims.

Having described my invention, I claim:

1. In a washing machine, a frame including a pair of end members having aligned openings, a shell arranged between and supported by the end members, the shell comprising a tubular wall and ends for the wall, said ends having openings registering with the first named openings, a cylinder within the shell, trunnions detachably secured to the cylinder and entering the registering openings, carriers in the openings of the end members, means for detachably securing the carriers to the end members and serving to attach the shell ends to the end members adjacent said openings, sealing means on the carriers for sealing about the trunnions, cartridges in the carriers, and bearings in the cartridges rotatably supporting the trunnions.

2. In a washing machine, a frame including a pair of end members having aligned openings, a shell arranged between the end members, the shell including a tubular wall and ends secured to the wall, the ends having openings registering with the first named openings, rings at the inner sides of said ends engaged in the openings thereof, studs securing the rings to the end members to attach the shell ends to the end members, a cylinder within the shell, trunnions detachably secured to the cylinder and entering the registering openings, carriers seated in said rings and detachably secured to the end members by said studs, the carriers having sockets, means at the inner ends of the sockets for sealing around the trunnions, and removable bearings in the sockets for turnably supporting the trunnions.

3. In a washing machine, a frame including a pair of end members having aligned openings, a shell including a tubular wall extending between

and secured to the end members and end plates for the tubular wall secured at their outer edges to the tubular wall and having openings registering with the first named openings, rings at the inner sides of said end plates having flanges extending into the openings thereof, studs securing the rings to the end plates and securing the end plates to said end members, a cylinder within the shell, trunnions detachably secured

5 to the cylinder and entering the registering openings, carriers engaged in said flanges and detachably secured to the end members by said studs, the carriers having sockets, means at the inner ends of the sockets for sealing around the trunnions, and removable bearing means secured to the carriers and engaged in the sockets thereof to turnably support the trunnions.

LEO M. HARVEY.
